UNITED STATES PATENT OFFICE

ALFRED C. LEIGH, OF BELLEVUE, PENNSYLVANIA, ASSIGNOR TO DRAVO CONTRACTING COMPANY, A CORPORATION OF PENNSYLVANIA

ROOF STRUCTURE

Application filed January 3, 1931. Serial No. 506,356.

My invention relates to the construction of ships, boats, barges, scows, and lighters; and, while it is applicable to buildings of all sorts, it finds practical application in the construction of roofs for deck-houses, hatchways, and the like, and in such application I shall show and describe it.

Fig. I is a view in side elevation of a barge, having a deck-house covered by the roof of my invention. Fig. II is a fragmentary view to larger scale, showing diagrammatically in perspective details of the structure in which my invention is found. Fig. III is a view similar to Fig. II showing other details. Fig. IV is a view in vertical and transverse section on the plane indicated at IV—IV, Fig. III.

Barges for transportation by water of merchandise or heavy material in bulk, decked over for purposes of protection, are provided, for facility in loading and unloading, with large hatchways. It is requisite that the roof above such hatchways shall be removable, and preferably removable in entirety, so that when removed the whole of the hatchway opening shall be free and unobstructed; it is desirable that when applied the roof shall be smooth-surfaced and water-tight; and it is to the achievement of these desirable ends, simply, effectively, and economically, that this invention is directed.

The barge of Fig. I includes a hull 1 and a deck 2. Through the deck a hatchway 20 is formed, and over the hatchway a deckhouse comprising walls 3 and a roof 30 is built. The whole structure is ordinarily built of sheet steel, and structural shapes of steel. The upper edge of the deck-house wall is, by means of structural shapes, provided with a stepped flange 5, including two treads and two risers, as shown in Figs. II and III.

The roof 30 is, as a matter of practical necessity, formed of a succession of sections, arranged side by side throughout the length of the deck-house; and, disregarding for present purposes the particular formation of the end sections, these sections are (and all of them are, so far as concerns the meeting edges of two adjacent sections) identical. Each section consists essentially of a web of metal, to

which, although it might be level, is here shown to be curved to a low arch, to span the deck-house walls from side to side. To the web of metal 4, at opposite ends, lengths 6 of channel beam are united, and upon these the roof section rests when applied to the stepped flange of the deck-house wall. The channel 6 rests on the outer and lower tread of the stepped flange 5, as is clearly shown in Figs. II and III.

Along each side of a roof section which in the assembly is to meet a like edge of adjacent section, the roof section is provided with the following structural features, illustrated in detail in Fig. IV. (1) The web 4 of which the section essentially consists is provided with a downwardly extending flange. Such a flange is conveniently formed by bending downward a marginal portion 7 of web 4 and by extending such bent-down margin by securing to it a plate 9. (2) Upon the outer face of such downwardly extending flange a gutter is formed. This is conveniently accomplished by securing to the flange a Z-bar 11. The free flange of the Z-bar stands vertically, and rises to a level slightly below the general plane of the upper and outer surface of the web 4. The Z-bars extend to the ends of the sections, and the gutters which they form discharge, as shown in Fig. II, to the outside of the inner riser of the stepped flange 5. (3) The marginal flange of plate 4 is at its lower extremity bent outward, to form exteriorly beneath the Z-bar 11 a supplemental trough. This trough also, as shown in Fig. II, discharges beyond the inner riser of the stepped flange 5. (4) To the upper face of web 4 and adjacent the edge of the section a strip 8 is secured. The unions here and elsewhere may conveniently be, and preferably will be, weld unions.

In the assembly two roof sections are brought to position with adjacent edges arranged as shown in Fig. IV, and the structure is completed by the application of a sealing strip 12. This is essentially a strip of steel, of such width as to rest on either side upon the webs 4, lying snug between the strips 8 upon adjacent sections, and spanning the interval between the downward extending

flanges 7. At its ends, the strip 12 is shaped to overlie the outer faces of the channel beams 6 of the cover sections, and to overlie also the outer and lower tread of the stepped flange 5, to which stepped flange the strip at its ends may be secured, as by the bolts 13 (Fig. III). The strip carries on its nether face outstanding flanges which in the assembly depend into the gutters formed as aforesaid by the 10 Z-bars 11. Accordingly, in convenient structure, to the strip 12 a length of steel channel-bar 14 is secured, and this channel-bar in the assembly comes to place immediately above the two vertically standing flanges of the 15 Z-bars 11 of the two roof sections, with the marginal flanges of the channel depending externally of the assembled flanges of the two Z-bars, as is particularly illustrated in Fig. IV.

Such being the details of construction, and with attention directed specifically to Fig. IV, these things are to be remarked: first, the closure which is provided of the seam between adjacent sections interrupts the smooth exterior roof surface to the extent only of the negligible thickness of the strips 8, and 12; the roof is substantially smooth, without obstructions, such as might on navigable streams be a source of difficulty, because of contact of overhanging branches of trees or of other overhanging bodies; second, the closure is of labyrinth character and effective to prevent access of water to the contents of the barge. Such rain water as may drive or seep beneath the strip 12, and between the nether surface of the strip 12 and the upper surface of the webs 4, will have access to the gutter which is formed by and between the downward extending flange upon web 4 and the Z-bar 11. Passing through this gutter longitudinally, that is to say, transversely, of the barge, such water will be discharged at the ends, externally of the stepped flange of the deck-house wall. And if indeed rain should drive in with such violence as to accumulate on the outer surfaces of the Z-bars 11, the troughs 10 will serve to catch the small amount and deliver it externally of the deck-house wall. It will be perceived that this cover is secure and adequate, without the aid of water-proof tarpaulin or the like.

I claim as my invention:

1. A roof structure for the hatchway of a barge or other vessel, secure against weather, and offering minimum obstruction to travel, including, in combination with opposite walls extending along opposite fore-and-aft edges of the hatchway, a plurality of roof sections applicable to and removable from such walls and adapted to be applied side by side and to extend abeam, the adjacent edges of two sections being provided each with an upstanding strip and a downwardly extending marginal flange, a gutter formed upon the face of each marginal flange, and a cover strip

resting upon two assembled sections between the upstanding strips thereof and overlying such gutters.

2. In a roof structure for the hatchway of a barge or other vessel, secure against the weather, and offering minimum obstruction to travel, the combination of walls with stepped flanged upper edges extending along opposite fore-and-aft edges of the hatchway, a plurality of roof sections adapted to be applied abeam and to rest at opposite ends upon said walls, each roof section consisting essentially of a web of sheet metal and two lengths of channel beam united to it across its opposite ends, which lengths of beam when the roof section is applied rest upon outer tread surfaces of the stepped hatchway walls, the webs of sheet metal of two adjacently applied roof sections being provided with downward extending marginal flanges and each such flange being provided with a gutter, which gutters when the parts are assembled extend outwardly beyond risers of the stepped hatchway walls, and a cover strip with downturned ends applicable to two assembled roof sections and in the assembly overlying the webs of the two sections adjacent their marginal gutter-carrying flanges, the ends of the cover strips overlying the ends of the roof sections and engaging tread surfaces of the stepped hatchway walls.

In testimony whereof I have hereunto set my hand.

ALFRED C. LEIGH.
